Richard Ramsay.

UNITED STATES PATENT OFFICE.

RICHARD RAMSAY, OF BRACEVILLE, ILLINOIS.

APPARATUS FOR STOPPING CARS.

SPECIFICATION forming part of Letters Patent No. 348,773, dated September 7, 1886.

Application filed May 29, 1886. Serial No. 203,597. (No model.)

To all whom it may concern:

Be it known that I, RICHARD RAMSAY, a citizen of the United States of America, residing at Braceville, in the county of Grundy and State of Illinois, have invented certain new and useful Improvements in an Apparatus for Stopping Box-Cars, of which the following is a specification, reference being had therein to the accompanying drawings.

This invention relates to certain improvements in an apparatus for stopping box-cars at a given and required place—as, for instance, at a coal-shaft, where it is required that the cars to be loaded must be stopped at a certain place every time, so that the apron of the coal-chute can be properly entered in the cars through the doorway at the side, and so the apparatus used for distributing coal in cars can be properly entered in the cars through the opposite doorway from the coal-chute.

The construction and operation of this apparatus is fully set forth and explained in the following specification and claims, reference being had to the accompanying drawings, and the letters and figures thereon, which form a part of this specification, in which—

Figure 1 is a perspective view of the apparatus as it would appear in service stopping a car. Fig. 2 is a detailed view on line x , showing a cross-section of the swinging beam of the apparatus, and also of the sill to which said beam is pivoted, and a side view of its supporting-arm and the lever and connecting-rod for operating the apparatus; and Fig. 3 is a top plan view of the swing-beam or buffer of the apparatus pivotally secured to a bed-sill.

C represents an ordinary box-car resting on the railway-track rails on platform-scales at a coal-shaft, where it is stopped to be loaded with coal.

S represents a bed-sill securely anchored to the ground at one side of and parallel with the railway-track rails.

B represents a beam or buffer pivotally and firmly secured to sill S, and arranged in an inclined position parallel with and over bed-sill S, with its extending free end at a height proper to engage the lower part of the jamb J of a box-car doorway when swung from its normal position, so as to engage a car.

D represents an arm arranged in a perpendicular position and pivotally secured at its

lower end, in box E, to bed-sill S, and having its upper end bent or formed at about right angles with its perpendicular part and arranged over and pivotally connected with beam or buffer B, as shown at G, for the purpose of supporting the free extending end of said beam or buffer, so it can be swung to one side. A chain or rod may be used to hang the free end of said beam or buffer in place of the arm D, where there are conveniences for so doing.

P represents a platform arranged at one side of beam or buffer B, of proper form and height for an operator to stand upon to operate the apparatus; but the apparatus may, however, be operated from the ground, if so desired.

L represents a hand-lever fulcrumed to platform P, having its free end extending above said platform, and connected at its lower shorter end with beam or buffer B through the medium of a connecting-rod, R. Said beam or buffer is shown as being pivoted at its lower end by a bolt, Z, passing down through it and sill S, and as being backed and re-enforced by a block, F, bolted to said sill; but other substantial means may be employed to pivotally secure said beam or buffer at that end.

By operating lever L the free end of beam or buffer B can be swung from its normal position to one side, as shown by dotted lines in Figs. 2 and 3, so as to engage the lower part of the door-jamb J of a box-car when the car reaches the proper place to be stopped.

When cars which are to be loaded are brought to a coal-shaft, they are run very slow into proper place by holding their brake-shoes close to their wheels, so that when they are stopped by engagement with the beam or buffer B their brake prevents reaction, and the car is brought to a dead stand at the exact place desired.

When the beam or buffer B is not in service it is brought to rest over and parallel with bed-sill S, so as to be out of the way from an approaching or passing car.

The cars approach their stopping-place from the direction indicated by the arrow in Fig. 1, and the apparatus is so arranged as to properly engage their door-jamb when thus brought to position; but a duplicate beam or buffer, B, may be used, arranged in a reverse position, so that cars may be stopped when

approaching from either direction. Flat cars may be stopped with like effect by engaging them at some convenient part.

Having thus described my invention, what I claim as new and useful, and desire to secure by Letters Patent, is as follows, to wit:

1. In an apparatus for stopping box-cars, the beam or buffer B, arranged substantially as set forth and pivotally secured to a fixed sill or anchor at its lower end, and adapted to have its free extending end swung to one side, for the purpose specified.

2. In the apparatus described, the combination, with the beam or buffer B, of the supporting-arm D and means, substantially as set forth, for operating said beam or buffer, as and for the purpose specified.

3. In the apparatus described, the combination of beam or buffer B and means for supporting its free extending end with the lever

and connecting-rod R, substantially as and for the purpose set forth.

4. In an apparatus for stopping box-cars, the combination of the swinging beam or buffer B, arm D, lever L, and connecting-rod R, constructed and arranged to operate substantially as set forth.

5. The combination of beam or buffer B, having its lower end pivotally secured to sill S by means of bolt Z, re-enforcing block F, supporting-arm D, lever L, and connecting-rod R, arranged to operate to give lateral movement to the free extending end of said beam or buffer, substantially as and for the purpose set forth.

RICHARD RAMSAY.
